POWER LINE STANCHION

Ross Forney, Renner, Tex., assignor to Forney
Engineering Company, Dallas, Tex.

Filed Oct. 11, 1972, Ser. No. 296,709

Term of patent 14 years

Int. Cl. D13—03

U.S. Cl. D26—12

FIG. 1

FIG. 2

FIG. 1 is a front elevational view of the power line stanchion and the undisclosed rear and side are substantially identical to the front and side shown in FIG. 2 respectively; and

FIG. 2 is a side elevational view of the power line stanchion shown in FIG. 1.

I claim:

The ornamental design for a power line stanchion, as shown and described.
